UNITED STATES PATENT OFFICE

101,089

DESIGN FOR A COMBINATION COMMODE AND MUSICAL INSTRUMENT CABINET

Ivan Ročić, New York, N. Y.

Application November 8, 1935, Serial No. 59,448

Term of patent 14 years

To all whom it may concern:

Be it known that I, Ivan Ročić, a citizen of the Kingdom of Croatia, Jugoslavia, and a resident of the city of New York, county of New York, and State of New York, have invented a new, original, and ornamental Design for a Combination Commode and Musical Instrument Cabinet, of which the following is a specification, reference being had to the accompanying drawing, forming part thereof.

Fig. 1 is a top plan view of the combination commode and musical instrument cabinet showing my design.

Fig. 2 is a front view.

Fig. 3 is a rear view—and

Fig. 4 is a bottom plan view thereof.

I claim:

The ornamental design for a combination commode and musical instrument cabinet as shown.

IVAN ROČIĆ.
